CARTON

Ralph Edmund Ariail, Summit, Ill., assignor to
 Corn Products Refining Company, New York,
 N. Y., a corporation of New Jersey

Application September 23, 1938, Serial No. 231,302

3 Claims. (Cl. 229—51)

This invention relates to cartons made of cardboard or other similar material.

One of the objects of the invention is to provide a carton formed with an opening line or series of perforations which weaken the cardboard so that it may be broken to open the package, in an arrangement, however, which prevents pulverulent material from sifting out through the perforations. This non-sifting feature makes it unnecessary for the carton, if used for packaging powdered material, to be provided with a cover or wrapper.

Another object of the invention is to provide a carton perforated or weakened along a proposed line of opening in such manner that the opening of the package will involve a minimum of obliteration or disfigurement of printed matter on the face of the carton, that is, will involve a minimum of defacement or change in the appearance of the package after it has been opened.

Another object of the invention is to provide a carton having a tuck-in closure flap, of new and improved construction, which will enable the carton to be easily opened and which will serve to close the carton again with reasonable security, preventing, for example, contamination of the partially used contents with dust, dirt or the like.

A further object of the invention is to provide a carton of the type indicated above which will be very strong, especially against thrust along its major dimension.

A further object of the invention is to provide cartons of the type indicated, the blanks for which can be cut out of sheets of cardboard without waste and with the use of a minimum amount of material consistent with strength, durability and tightness of the package.

A further object is to provide a carton of the type indicated which can be made, filled and sealed by the employment of machinery and procedures now commonly in use, with only minor changes in such machinery and procedures.

A further object of the invention is to provide a carton of the tuck-in flap type which may be opened in a very simple and easily understood manner, and for the opening of which the directions on the package can be brief and simple.

The invention is illustrated in the accompanying drawings in which Figure 1 is a plan view of the blank cut, scored, for folding, and perforated, in order to produce a carton in accordance with the principles of the invention.

Figure 2 is a view in perspective of the blank partly folded and with the tuck-in flap glued to the adjacent panel.

Figure 3 is a plan view of two cut and scored blanks, illustrating a modification of the invention intended to economize cardboard.

Figure 4 is a view in perspective, with parts broken away, of the carton ready for filling.

Figure 5 is a perspective view of the filled and sealed carton.

Figure 6 is a perspective view, on enlarged scale, of the upper end of the carton after it has been opened, parts being broken away to show the position of the tuck-in flap with the carton re-closed; and

Figure 7 is a sectional view on line 7—7 of Figure 4.

Referring first to Figures 1, 2 and 4 to 7, inclusive:

The carton is made from a cardboard blank 10 which is cut and scored, for folding, in order to produce a six-sided box, the front, back, side, top and bottom panels of which are made up of the following elements: 11 is the front panel formed with a series of perforations 12 which extend inwardly from the upper corners of the panel and for the rest of the way run parallel to the upper edge of the panel. The back panel is designated 13, and the blank is scored along the lines 14—14 and 15—15—15, and is cut at 16—16—16—16—16 to provide for side members 17—18 and 19—20, which make up side panels of double thickness; a bottom panel 21 having tabs 22—23; and a top panel 24 having tabs 25 and 26, the tab 26 being narrower than 25 for reasons which will appear. The top panel is formed, in the cutting and scoring operation, with a tuck-in tab 27, scored for folding along the line 28.

The terms "top," "bottom," "front," and "sides" are used merely for convenience, in the description and in the claims, having reference to the position of the filled carton as shown in Figure 5. It will be understood that the terms are entirely relative, depending upon the printing, if any, on the carton or the intended position of the carton on the shelf. The tuck-in flap is shown as on the panel of smallest area, referred to as the "top." This is not essential. It might be along one of the other edges. In the filling position, as will be seen, one of the sides becomes the top. Cardboard ordinarily has a grain, the fibres running generally in one direction across the board. This grain is indicated by the shade lines on Figures 1 and 3, the blank

being preferably cut so that the grain will run lengthwise of the front, back and side panels, and transversely of the top panel and its tuck-in flap, for reasons which will appear.

5 The blank, as shown in Figure 1, is first folded as indicated in Figure 2, and the tuck-in flap 21 glued to the inside edge of the front panel 11. The glue area is indicated in Figure 1 at 29, and is preferably about the width of the space 10 between the perforations 12 and the upper edge of the front panel so that a considerable portion of the flap extends below the line of perforations and is not glued to the front panel. This portion of the flap is, however, closely pressed 15 against the front panel, this pressure being increased by the fact that the fold at 28 runs across the grain of the paper. This arrangement effectively prevents any sifting out of pulverulent material when the contents of the package 20 consists of material of this sort.

The folded structure of Figure 2 then goes to the filling machine. It enters the machine, top end first with the front and back panels vertical, and is opened up to its box-like shape by a finger 25 which engages the short top flap 26. The side panel at the bottom is then formed by folding in the tabs 22-26, and the side members 17-18, as shown in Figure 4, and gluing or otherwise securing these parts together which is done with 30 a block in carton. The other side of the box is open for filling and the carton goes into the filling machine with this side up. When filled, the tabs 23-25 and the side members 19-20 are folded down and glued together so as to close and seal 35 the package; the closed and sealed package being shown in Figure 5.

To open the package, it is only necessary to exert sufficient pressure along the line of perforations 12, which can be done with the fingers, to 40 break the front panel along this line, after which the top panel is raised, tearing the material along the scores 14a-14a between the top panel and the tabs 25-26. The material tears easily at these places because the tear is lengthwise of the grain. 45 A stiff, reinforced tuck-in flap is now provided consisting of the member 27 and the portion 30 of the front panel between the line of perforations 12 and the upper edge 31 of the front panel, as shown in Figure 6. This tab may be used to 50 close the package in case the entire contents are not used at the first opening.

It will be understood that the gluing together of cardboard requires considerable pressure where the glued area is small in order that the bond 55 may be secure and permanent. It would not be practical to fill the carton through the top and then attempt to glue the tuck-in tab to the front panel. By accomplishing this operation when the folded blank is flat, as shown in Figure 60 2, any desired pressure may be exerted.

The carton, as described, is very strong as against end pressure, due to the two ply thickness of the side panels, so that it is not likely to be crushed when the cartons are packed one on top 65 of the other. The double thickness of the walls also reinforces the carton as against pressure as between its front and back panels.

A carton which may not perhaps be quite as strong as the one shown in Figures 1, 2 and 4 to 7, inclusive, but which will economize cardboard, is 70 illustrated in Figure 3 which shows two blanks for forming cartons of this type. These blanks

correspond to the blank shown in Figure 1 except that in each case the side member 17a-20a and the tabs 22a and 25a are made half width. As indicated in Figure 3 the blanks may be cut from the sheet without waste.

While the invention has been shown and described in preferred embodiments, it will be understood that the intention is to cover by patent all equivalents and all modifications within the scope of the appended claims.

I claim:

1. A six-sided carton made from a single blank of cardboard or the like which when ready for filling comprises: a front panel having a weakened opening line extending in the direction of 15 the width of the panel; a top panel having a tuck-in flap glued to the inner face of the part of the front panel between the weakened line and the upper edge of the panel and extending below said weakened line; a side panel consisting 20 of overlapped and glued top and bottom tabs and side members to provide a double thickness for the major length of the panel and triple thickness at its opposite ends; and at the other side of the carton side members and top and bottom 25 tabs adapted to be folded down and secured together to form a similarly reinforced panel when the carton has been filled.

2. A six-sided carton made from a single blank of cardboard or the like which when ready for 30 filling comprises: a front panel having a weakened opening line; a top panel having a tuck-in flap glued to the part of the front panel between the weakened line and the upper edge of the panel and extending below said weakened line; a side 35 panel consisting of overlapped and glued top and bottom tabs and side members; and at the other side of the carton, side members and top and bottom tabs adapted to be folded down and secured together when the carton has been filled; the 40 carton being composed of grained cardboard with the grain of the cardboard running lengthwise of the front, back and side panels and at the junction of the top tabs with the top panel, but transversely of the top panel and its tuck-in flap, 45 whereby the top tabs will tear along straight lines at their junction with the top panel when the carton is opened, and whereby the tension in the fibers of the tuck-in flap will hold it in firm contact with the inner face of the front panel below 50 the said weakened opening line.

3. A six-sided carton made from a single blank of cardboard or the like which when ready for filling comprises: a front panel having a weakened opening line extending in the direction of 55 the width of the panel; a top panel having a tuck-in flap glued to the inner face of the front panel between the weakened line and the upper edge of the panel and extending below said weakened line; a side panel consisting of overlapped and glued top and bottom tabs and side members; at the other side of the carton, side members and top and bottom tabs adapted to be folded down and secured together when the carton has been filled and the side members on each side of the 60 carton being one of substantially the width of the carton and the other of half width for economy of cardboard and to form double thickness reinforcements extending lengthwise of the carton at two diagonally opposed corners thereof.

70

RALPH EDMUND ARIAIL.
